UNITED STATES PATENT OFFICE.

JAMES H. REED AND FORREST W. BEALE, OF LYNN, MASSACHUSETTS,
ASSIGNORS, BY MESNE ASSIGNMENTS, TO THE GLOBE BUTTONHOLE
MACHINE COMPANY, OF KITTERY, MAINE.

BUTTON-HOLE-STITCHING MACHINE.

SPECIFICATION forming part of Letters Patent No. 389,010, dated September 4, 1888.

Application filed June 28, 1886. Serial No. 206,393. (No model.)

To all whom it may concern:

Be it known that we, JAMES H. REED and FORREST W. BEALE, both of Lynn, in the county of Essex and State of Massachusetts, 5 both citizens of the United States, have invented a new and useful Improvement in Button-Hole-Stitching Machines, of which the following is a full, clear, and exact description, reference being had to the accompanying 10 drawings, forming a part of this specification, in explaining its nature.

The invention is an improvement upon that described in our application for Letters Patent of the United States filed May 28, 1886, 15 Serial No. 203,506; and it consists in the novel construction and combination of parts herein-after described and claimed.

Referring to the drawings, Figure 1 is a view in vertical central section of a button-hole-stitching machine containing our improvements. Fig. 2 is a view in front elevation of the upper arm or bracket and its cap. Fig. 3 is a view in plan of the machine inverted. Fig. 4 is an enlarged view in section 20 and elevation illustrating the relation which the needles bear to each other and to the loop-forming devices while a stitch is being made, and also showing the manner of supporting the lower curved needle. Fig. 5 is a view 25 upon the same section, showing in section and elevation the same parts, but in a different position. Fig. 6 is a plan view, inverted, of the upper thread-loop engaging and spreading devices, showing the loop opened or spread 30 thereby. Fig. 7 is a view in plan, inverted, of the same devices, showing the loop-engaging hook or point in the act of engaging the loop. Fig. 8 is a view of the same parts shown in Figs. 4 and 5, but representing them in a different position. Fig. 9 is a view in perspective to further illustrate the construction and operation of said parts. Fig. 10 is a view to 35 illustrate the recess formed in the side of the lower curved needle and the relation which it bears to the upper needle at the end of its upward movement. Fig. 11 is a detail view of a portion of the upper needle, the lower curved needle, and a part of its supporting-block, representing the position of the lower curved 40 needle in relation to the upper needle at the

end of its upward movement. Fig. 12 is a plan view of the lower curved needle at the end of its upward movement, showing the recess in its side and the relation which the straight needle bears to it.

A is the upper or straight needle. It is like that described in our said application, and is operated as therein set forth.

a is the take-up for the upper thread. It comprises an arm, a', which is pivoted at a² 60 to the cap a³ at the end of the bracket a⁴. It has a spring, a⁵, by which it is lifted or moved upwardly, and it is moved downwardly by a pin, a⁶, fastened to the needle-bar projecting through the slot a⁷ in the cap of the machine 65 and arranged to bear upon the upper surface of the take-up arm. This upper surface is provided with an inclined section, a⁸, upon which the pin bears in moving it downward, and with a section, a⁹, which, when the take-up has been moved down sufficiently far, 70 becomes parallel with the slot or line of movement of the pin, so that the pin, needle-bar, and needle continue their downward movement while the take-up remains stationary, 75 and the take-up is held by the pin in this stationary position until the needle-bar in its upward movement lifts the pin above this straight section a¹⁰, when the spring returns it to its highest position.

55

80

B is the throat of the machine.

C is the lower curved needle. It is supported by a block or carriage, c, which is supported in a curved guideway or recess, c', in the side of the arm or bracket c², fastened to 85 the under surface of the bed of the machine. This block or carriage c is provided with a movement to or very nearly to the under surface of the work-plate, approaching the plate as nearly as possible in order that the curved 90 needle may be made as short as possible, and may be rigidly held or supported during its reciprocation. By securing it to the upper end of a block or carriage movable in a suitable recess or guideway we are enabled to obtain this result in a cheap and desirable way. The block or carriage c is movable in the curved guideway, which is struck upon an arc of a circle by means of a cam, c³, which is like the cam described in our said application, the 95 100

slide-bar c^4 and the link c^5 , which connects the end of the slide-bar with a pin or post, c^6 , extending laterally from the block or carriage c . The needle C is also provided with a recess, c^7 , formed in the edge nearest the line of reciprocation of the straight needle A and near the point of the needle. This construction is well shown in Figs. 11 and 12, and the position which the thread bears in relation to it to provide a narrow opening or space for the reception of the point of the straight needle is well represented in the said Figs. 11 and 12.

The take up D for the lower thread, instead of being pivoted to a stationary point, as described in our said application, is made movable, or travels with the carriage or block carrying the curved needle. This enables us to operate it more closely or finer than the take-up in said application can be operated. It is, moreover, less complicated in construction and works more easily. It is pivoted to the end of the slide-bar c^4 , so as to swing vertically in relation thereto. It is moved upward upon the upper movement of the curved needle by means of the inclined or wedge-shaped surface d upon its upwardly-bent end d' , which is arranged to strike a surface or shoulder, d'' , at the proper interval, and by riding thereon throw the end of the take-up upward to slacken the thread immediately upon the end of the upward movement of the curved needle, so as to form upon the end thereof a loop through which the upper needle immediately passes. After the upper needle has entered this loop, this take-up arm is immediately moved downward, upon the backward movement of the slide-bar c^4 and of the curved needle, by means of the spring d^3 , which is fastened to the slide-bar c^4 or link c^5 and bears against the take-up bar. The time of the operation of the take up is the same as that of the take-up described in our said application, the principal difference being that the take-up herein described travels with the slide-rod and curved needle, while the other does not.

The upper thread-loop engaging and spreading mechanism varies from that described in our said application in that the upper thread-loop is caught by a sliding point or hook, and is by that point or hook moved to a position to bring the thread opposite the spreading point or hook, which is immediately operated or moved to open the loop, it being operated by the further movement of the bar or block carrying the loop-engaging point as it continues its movements away from the throat, the movement being stopped for an instant to permit the upper needle to draw up the thread to bring it to a shorter angle, in order that the spreading-hook may more surely engage it. The loop, when thus caught and spread, will be held by the upper needle, which will have lifted above the work, and by the loop-engaging hook or arm and by the loop-spreading hook or arm, which have been moved away from each other, so that the loop is held spread or open in the line of reciprocation or move-

ment of the lower curved needle. The lower curved needle upon passing through the loop taking its thread with it, the spreading hook or arm and the loop-engaging hook or arm are immediately returned to their original position to release the loop.

E is the loop engaging hook or arm. It is provided with a straight horizontal movement by means of the slide-bar e , to the end of which is secured the lever e' , pivoted at e^2 , the link e^3 , the bent lever e^4 , pivoted at e^5 , and the cam e^6 , the arm e^7 of the bent lever having a cam pin, which enters a cam-groove in the cam-disk. The cam is different from that described in our said application, in that it moves the loop-engaging hook or arm E parallel with the line of reciprocation of the upper needle to engage the upper thread, and then becomes stationary, while the upper needle continues its upward movement, and it is then immediately moved forward again to cause the loop-spreading arm or hook to engage the thread and also to spread the loop.

F is the loop-spreading hook or arm. It is formed upon the inner side of the curved arm f , which is pivoted at f' to the under surface of the bed-plate, and there is an extension, f^2 , which has the curved edge or cam f^3 , which extends across the path or line of reciprocation of the loop-engaging hook, and a cam pin or stud, f^4 , carried by the slide bar or plate upon which the loop-engaging hook or arm is formed, is adapted to come in contact with this cam or curved surface f^3 immediately upon the beginning of the second portion of the outward movement of the loop-engaging hook and to move the loop-spreading hook F transversely across the line of reciprocation or movement of the loop engaging and carrying hook, and so that the point F shall engage one of the threads of the loop and shall carry it transversely to the loop-engaging hook, so that by the continued movement of the loop-engaging hook and the loop-spreading hook the loop is opened sufficiently wide to receive the lower needle. Upon the reverse movement of the loop-engaging hook the loop-spreading hook is returned to its original position by means of the spring f^5 . This loop-spreading mechanism is an improvement upon that described in our said application, in that less thread is required for forming the loop, and the movements of the loop-engaging hook and loop-spreading hook are made easier, and there is less thread to take up.

It will be seen that the take-up a for the upper thread is placed in close proximity to the needle A , and so that it takes the thread directly from the eye thereof, instead of being arranged back or behind the cap or head of the machine, as has heretofore been the case. This construction we consider to be an improvement, because it enables us to take up the thread directly from the needle with less friction and more promptly and with less wear and strain upon the thread than has heretofore, so far as we know, been the case.

Having thus fully described our invention, we claim and desire to secure by Letters Patent of the United States—

1. In a button-hole-stitching machine, the combination of the upper needle, the curved lower needle, a reciprocating block or carriage supporting the same, a curved guide or recess close to the throat, in which said block or carriage is movable, a take-up for the lower thread moved horizontally, having the inclined surface or edge, *d*, adapted to come in contact with a shoulder as it is moved, whereby it is moved upwardly, and a spring for moving it downwardly when the incline is not in contact with the shoulder, substantially as described.
2. In a button-hole-stitching machine, the combination of the bed of the machine, having a throat formed therein, a clamp-plate and means for feeding the same, the reciprocating straight eye-pointed needle, the lower loop-spreading devices, comprising a horizontally-movable loop-engaging hook or point, *E*, and means for moving the same to engage the upper thread when presented to it by the upper straight needle, and loop-spreading hook or point *F*, formed upon the end of a pivoted

arm and movable transversely upon the arc of a circle across the line of movement of the loop-engaging hook or point *E*, whereby the loop is opened or spread, and the reciprocating eye-pointed lower curved needle having a notch or recess, *c*, near its point, substantially as described.

3. The combination, in a button-hole-stitching machine, of a bed having a throat, a clamp-plate, and means for feeding the same, an upper reciprocating eye-pointed straight needle, a lower reciprocating eye-pointed curved needle having a notch or recess, *c*, near its point, a loop-engaging hook or point, *E*, and means, substantially as specified, for moving it upon a straight line below the work-plate, a cam pin or stud carried thereby, a curved pivoted arm having a loop-spreading hook or point, *F*, and a curved surface or cam, against which said cam pin or stud is brought in contact, all substantially as described.
